UNITED STATES PATENT OFFICE.

CARL H. BISSELL AND ELDA G. SMITH, OF SYRACUSE, NEW YORK, ASSIGNEES TO CROUSE-HINDS COMPANY, OF SYRACUSE, NEW YORK, A CORPORATION OF NEW YORK.

ELECTRICAL CONNECTION.

1,222,721.

Specification of Letters Patent. Patented Apr. 17, 1917.

Application filed January 8, 1914. Serial No. 810,993.

To all whom it may concern:

Be it known that we, CARL H. BISSELL and ELDA G. SMITH, citizens of the United States, and residents of Syracuse, in the county of Onondaga and State of New York, have invented a certain new and useful Electrical Connection, of which the following is a specification.

This invention has for its object the production of an electrical connection or socket, particularly applicable for use on railway cars for receiving the plug in the feed circuit for charging at stations the storage batteries of the cars; and the invention consists in the combinations and constructions hereinafter set forth and claimed.

In describing this invention, reference is had to the accompanying drawings, in which like characters designate corresponding parts in all the views.

Figure 1 is a longitudinal sectional view of our socket with one form of plug therein.

Fig. 2 is a longitudinal sectional view of the socket.

Figs. 3 and 4 are opposite end elevations of parts seen in Fig. 2.

Fig. 5 is an end view of the body of the socket, the contents being removed.

Figs. 6 and 7 are elevations of the sleeve terminal and the central terminal, respectively.

This electrical socket comprises, generally, a body, an outer sleeve terminal located in the body and including a circular series of contacts, and spring means acting on the contacts to compress the same radially. This socket also preferably includes a central terminal capable of lateral movement relatively to its axis.

1 is the body composed of a block of insulation, the body having a lengthwise recess 2 opening through one end thereof and terminating short of the other end, this recess including an enlargement 3 at one end which opens through one end face of the body 1.

4 is the outer sleeve terminal located in the recess 2 and secured therein at its inner end, the sleeve being slotted longitudinally from its outer end, the slots terminating short of the inner end of the sleeve and forming a circular series of lengthwise clamping contacts 5. The outer ends of the contacts are flared outwardly at 6 in the

enlargement 3 and form an entrance for 55 guiding the plug into the sleeve. Preferably said outer ends 6 of the contacts 5 terminate between the inner and outer ends of the enlargement 3 and their outer extremities are spaced apart from the inner 60 face of the peripheral wall of said enlargement.

The spring means, acting radially on the contacts 5, is here shown as an annular coiled spring 8 expansible and contractile 65 in diameter and encircling the free ends of the contacts 5 in the rear of the outwardly flared ends 6 of the contacts, the spring 8 being located in the enlargement 3 of the recess 2 and being held from undue axial 70 movement by the bottom wall 9 of the enlargement and by the rear sides of the flared ends of the contacts 5, Fig. 2. The spring also engages the inner circumferential wall of the enlargement after the contacts have 75 been spread outwardly a predetermined amount, and hence prevents undue spreading or distortion of the contacts. The annular end surfaces of the spring 8 engaged with the bottom wall of the enlargement 3 80 and the rear sides of the flared ends 6 of the contacts 5 are rounding in cross-section and are thus free to roll more or less on the surfaces engaged therewith for reducing the liability of binding and straining of 85 said spring and the flared ends 6.

The inner end of the sleeve 4 is located in an annular groove 10, Figs. 2 and 5, in the bottom 11 of the recess 2, and is held in position by means of screws 12 attached to 90 the inner end of the sleeve 4 and extending through the bottom 11 and threading into nuts 13 located in sockets 13^a on the outer side of the bottom 11.

Preferably, the sleeve is formed with T 95 shape slots 14, Fig. 6, the legs of which open through the inner edge of the sleeve, and the screws 12 have their heads located in the heads of the T slots and their shanks in the legs of the T slots and extending 100 through openings in the bottom 11 of the body 1.

15 is the central terminal which is located within the sleeve terminal 4 and is connected to the body 1 or the bottom 11 of the recess 105 to have a slight movement laterally relatively to its axis. As here shown, the terminal 15 includes a shank portion 16 ex-

tending through the bottom 11 of the recess 2 and held from rotation by a pin 17 extending transversely thereof into slots 18, Fig. 5, in the bottom 11.

5 Preferably, the terminal 15 is connected to the bottom 11 by a ball and socket joint, the bottom being formed with the ball 19, and the shank of the central terminal 15 having a concave washer 20 thereon which engages the ball on the front side thereof, and a nut 21 screwing on said shank and formed with a concave face engaging the ball 19 on the rear side thereof. The ball and socket joint pivotally connects the central terminal 15 to 10 the body 1. The outer end portion of the central terminal 15 is tubular and slotted to form a circular series of contacts 22.

15 The rear end of the shank 16 is threaded for the nut 21 and a jam nut 23 screwing 20 against said nut 21 and also for receiving a suitable wire coupling 24. The terminal 4 is also provided with a wire terminal as a shank 25 at one side thereof which extends through an opening in the bottom 11 of the 25 recess 2 and to the rear of the body 1 and on which a nut 26 turns against the bottom 11; the shank 25 is also provided at its rear end with a suitable wire coupling 27.

20 The nuts 21 and 23 serve to hold the central terminal in position and the nut 26 may serve to hold the outer sleeve terminal in position and the screws 12 may be dispensed with, if desired. The portions of the shanks 16 and 25, projecting to the rear of the bottom 11 of the body 1, are inclosed in a suitable housing 28 which is secured to the bottom 11 by screws 29.

25 When the sleeve 4 is being placed in position in the body 1, the screws 12 are placed 40 in the T slots 14, and when the sleeve 4 is being inserted in the recess 2, the heads of these screws 12 pass along lengthwise grooves 30 formed in the inner circumferential face of the recess 2. The shank 25 also 45 passes along another lengthwise groove 31 in the circumferential face of the recess 2.

30 32 designates the plug which is composed of a body of insulation 33 encircled by a sleeve contact 34 for entering the outer sleeve 50 terminal 4 of the socket and which supports the central terminal 35 for entering the tubular portion of the central terminal 15 of the socket, the central terminal 35 of the plug being located in the axial passage 36 in 55 the body 33 of the plug. The central terminal 35 is shorter than the sleeve contact 34 and is of such length as to enter the central terminal 15 of the socket just after the sleeve contact 34 enters the outer sleeve terminal 4 60 of the socket. The sleeve terminal 34 of the plug is provided with a wire terminal 37 extending through the rear end of the body 33 and provided with a wire coupling 38 at its rear end, and the central terminal 35 is 65 also formed with a wire terminal 39 extend-

70 ing beyond the rear end of the body 33 of the plug and having a wire coupling 40 at its rear end. The rear ends of the wire terminals 37, 39 are located in recesses in a block 41 of insulation at the rear end of the body 70 33 of the plug.

75 The body 33 and block 41 are held in position in a suitable housing by means of a threaded ring 43 screwing into the front end of the housing against a shoulder 44 on the body 33 and pressing the body 33 and block 41 rearwardly toward an internal annular shoulder 45 in the housing 42, against which the block 41 abuts. The construction of the plug forms no part of this invention. 80

85 In operation, the socket is located in a suitable housing not shown which is swiveled to the car or to the trucks thereof, and when it is desired to charge the battery of the car at a station, the plug, which is attached to the charging circuit at the station, is inserted in the socket. The plug is, of course, permanently connected in the charging circuit by wires usually located between the car tracks. Should the trainman neglect 90 to remove the plug before the train starts, the body will swing around until the pull on the plug, and the wires connected thereto, is in nearly a straight line when the plug will be withdrawn owing to the fact 95 that the train is in motion. However, this pull is not in an exact straight line, and owing to the annular coiled spring and to the movement of the central terminal 15 laterally relatively to its axis, wrenching 100 and distortion of the contacts 5 and 22 are avoided.

105 What we claim is:—

1. An electrical socket comprising a sleeve terminal having its inclosing wall provided with a circular series of lengthwise clamping contacts, the free ends of the contacts being flared outwardly, and an annular spring expandible and contractile in diameter, the spring encircling the contacts and being seated against the rear sides of said flared ends, substantially as and for the purpose described. 110

2. An electrical socket comprising a sleeve terminal slotted longitudinally from one end thereof, the slots terminating short of the other end forming a circular series of clamping contacts, the free ends of the contacts being flared outwardly, and an annular coiled spring encircling the contacts and being seated against the rear sides of the flared ends, substantially as and for the purpose specified. 115

3. An electrical socket comprising a body having an axial recess formed with an enlargement, a sleeve terminal arranged within the recess and provided with a circular series of lengthwise clamping contacts, and an annular spring expandible and contractile in diameter, the spring being arranged in the 120 125 130

enlargement and encircling and coacting with the contacts, substantially as and for the purpose set forth.

4. An electrical socket comprising a body 5 having an axial recess formed with an enlargement, a sleeve terminal arranged within the recess and provided with a circular series of lengthwise clamping contacts, portions of the contacts being extended outwardly in the enlargement, and an annular spring expandible and contractile in diameter, the spring being arranged in the enlargement and encircling the contacts and coacting with the outwardly extended portions of said contacts, substantially as and for the purpose specified.

5. An electrical socket comprising a body having a cylindrical recess formed with an enlargement at one end which opens through 20 one end of the body, a circular series of contacts extending into the recess and having their ends projecting into the enlargement thereof and flared outwardly, and an annular coiled spring encircling the contacts 25 within the enlargement, substantially as and for the purpose set forth.

6. An electrical socket comprising a body having an axial recess, a sleeve terminal arranged within the recess and provided with 30 a circular series of lengthwise clamping contacts, and an annular spring expandible and contractile in diameter and encircling the contacts within the recess, the inner face of the spring coacting with the outer faces 35 of the contacts and the periphery of the spring coacting with the inner face of the recess, substantially as and for the purpose described.

7. An electrical socket comprising a body 40 having an axial recess formed with an enlargement, a sleeve terminal arranged within the recess and provided with a circular series of lengthwise clamping contacts, portions of the contacts being extended outwardly in the enlargement, and an annular spring expandible and contractile in diameter, the spring being arranged in the enlargement and encircling the contacts, the inner face of the spring coacting with the 45 outwardly extended portions of said contacts and the periphery of the spring coacting with the inner face of the peripheral wall of the enlargement, substantially as and for the purpose set forth.

55 8. An electrical socket comprising a body having an axial recess formed with an enlargement, a sleeve terminal arranged within the recess and provided with a circular series of lengthwise clamping contacts, the 60 free ends of the contacts being extended outwardly in the enlargement and spaced apart from the inner face of the peripheral wall of said enlargement, and an annular spring expandible and contractile in diameter, the 65 spring being arranged in the enlargement

and encircling the contacts, the inner face of the spring coacting with the rear sides of the outwardly extended ends of the contacts and the periphery of the spring coacting with the inner face of said peripheral wall 70 of the enlargement, substantially as and for the purpose specified.

9. An electrical socket comprising a body having an axial recess provided with an annular engaging shoulder, a sleeve terminal 75 arranged within the recess and provided with a circular series of lengthwise clamping contacts, portions of the contacts being extended outwardly in advance of said shoulder, and an annular spring expandible 80 and contractile in diameter and encircling the contacts within the recess, one end of the spring engaging said shoulder and its other end engaging the outwardly extended portions of the contacts, substantially as and 85 for the purpose set forth.

10. An electrical socket comprising a body having an axial recess provided with an annular engaging shoulder, a sleeve terminal arranged within the recess and provided 90 with a circular series of lengthwise clamping contacts, portions of the contacts being extended outwardly in advance of said shoulder, and an annular spring expandible 95 and contractile in diameter and encircling the contacts within the recess, one end of the spring being formed with an annular surface convex in cross-section engaging said shoulder and the other end of the spring being formed with an annular surface convex 100 in cross-section engaging the outwardly extended portions of the contacts, substantially as and for the purpose specified.

11. An electrical socket comprising a body having an axial recess provided with an 105 annular engaging shoulder, a sleeve terminal arranged within the recess and provided with a circular series of lengthwise clamping contacts, portions of the contacts being extended outwardly in advance of said 110 shoulder, and an annular coiled spring expandible and contractile in diameter and encircling the contacts within the recess, one end of the spring engaging said shoulder and its other end engaging the outwardly 115 extended portions of the contacts, substantially as and for the purpose described.

12. An electrical socket comprising a body having an axial recess formed with an enlargement, a sleeve terminal arranged within the recess and provided with a circular series of lengthwise clamping contacts, the free ends of the contacts being extended outwardly in the enlargement, and an annular spring expandible and contractile in diameter, the spring being arranged in the enlargement and encircling the contacts, and one end of the spring engaging the inner end of the enlargement and its other end engaging the rear sides of the outwardly 120 125 130

- extended ends of the contacts, substantially as and for the purpose set forth.
13. An electrical socket comprising a body having an axial recess provided with an annular engaging shoulder, a sleeve terminal arranged within the recess and provided with a circular series of lengthwise clamping contacts, portions of the contacts being extended outwardly in advance of said shoulder, and an annular spring expansible and contractile in diameter, the inner face of the spring coacting with the outer face of the contacts and the periphery of the spring coacting with the inner face of the recess and one end of the spring engaging said shoulder and its other end engaging the outwardly extended portions of the contacts, substantially as and for the purpose set forth.
14. An electrical socket comprising a body having an axial recess formed with an enlargement, a sleeve terminal arranged within the recess and provided with a circular series of lengthwise clamping contacts, the free ends of the contacts being extended outwardly in the enlargement and spaced apart from the inner face of the peripheral wall of said enlargement, and an annular spring expansible and contractile in diameter, the spring being arranged in the enlargement and encircling the contacts, the inner face of the spring coacting with the rear sides of the outwardly extended ends of the contacts and the periphery of the spring coacting with the inner face of said peripheral wall of the enlargement, and one end of the spring engaging the inner end of the enlargement and its other end engaging the rear sides of the outwardly extended ends of the contacts, substantially as and for the purpose set forth.
15. An electrical socket comprising a body having an axial recess formed with an enlargement, a sleeve terminal arranged within the recess and provided with a circular series of lengthwise clamping contacts, the free ends of the contacts being extended outwardly in the enlargement and terminating between the ends of the enlargement and being spaced apart from the inner face of the peripheral wall of said enlargement, and an annular coiled spring expansible and contractile in diameter, the spring being arranged in the enlargement and encircling the contacts, the inner face of the spring coacting with the rear sides of the outwardly extended ends of the contacts and the periphery of the spring coacting with the inner face of said peripheral wall of the enlargement, and one end of the spring engaging the inner end of the enlargement and its other end engaging the rear sides of the outwardly extended ends of the contacts, substantially as and for the purpose set forth.
16. An electrical socket comprising a body formed with a cylindrical recess opening through one end thereof and terminating short of the other end; the body being formed with an annular groove in the bottom of the recess, a sleeve terminal located in the recess and having its inner end extending into the groove and means for holding the sleeve terminal in the groove, said means extending through the bottom of the groove, substantially as and for the purpose described.
17. An electrical socket comprising a body formed with a cylindrical recess opening through one end thereof and terminating short of the other end, a sleeve terminal located in the recess and formed with a T slot at its inner end, the leg of the T slot opening through the inner edge of the sleeve, and a fastening screw having its head located in the head of the T slot and its shank extending through the leg of the T slot and through the bottom of said recess, substantially as and for the purpose specified.
18. An electrical socket comprising a body formed with a cylindrical recess opening through one end thereof and terminating short of the other end, the body being formed with an annular groove in the bottom of the recess, a sleeve terminal located in the recess and formed with a T slot at its inner end, the leg of the T slot opening through the inner edge of the sleeve, and a fastening member having its head located in the head of the slot and its shank extending through the leg of the slot and through the bottom of said recess, substantially as and for the purpose specified.
19. An electrical socket comprising a body formed with a cylindrical recess opening through one end thereof and terminating short of the other end, the body being formed with a lengthwise groove in the inner face of the recess, and an opening extending through the bottom of the recess and communicating with the inner end of the groove, a sleeve terminal located in the recess, and means for securing the sleeve terminal in the recess, said means being of greater thickness than the wall of the sleeve terminal and being movable in the lengthwise groove, a portion of said means being extended into said opening, substantially as and for the purpose specified.
20. An electrical connection comprising an outer sleeve terminal which is expansible and contractile, and a central terminal within the sleeve and movable laterally relatively to its axis, substantially as and for the purpose specified.
21. An electrical connection comprising an outer sleeve terminal which is expansible and contractile, and a central terminal within the sleeve and movable laterally relatively to its axis, said terminal being pivoted at the

inner end of the sleeve, substantially as and for the purpose set forth.

22. An electrical socket comprising a supporting body, and a central terminal having 5 a rigid axial shank connected to the body to move laterally relatively thereto and a circular series of spring contacts for receiving a plug, the series of contacts being yieldable laterally relatively to the rigid shank 10 and to each other, substantially as and for the purpose set forth.

23. An electrical socket comprising a body formed with a lengthwise recess opening through one end and terminating short of 15 the other end, an outer terminal located in the recess and including a circular series of contacts fixed at their inner ends to the

body, a central terminal pivoted to the body at the inner end of the recess and having its outer end portion tubular and composed 20 of a circular series of contacts, and an annular coiled spring encircling the contacts of the outer terminal, substantially as and for the purpose set forth.

In testimony whereof, we have hereunto 25 signed our names in the presence of two attesting witnesses, at Syracuse, in the county of Onondaga, in the State of New York, this 22nd day of December, 1913.
